CALCULATING MACHINE

Myron Beitler, West Orange, and Terry L. Barner,
Orange, N.J., assignors to Litton Business Systems,
Inc., Orange, N.J.

Filed Aug. 2, 1973, Ser. No. 385,038

Term of patent 14 years

Int. Cl. D14—02
US. Cl. D26—5 C

FIG. 1

FIG. 2

FIG. 1 is a perspective view of a calculating machine showing our new design;

FIG. 2 is a top plan view thereof;

FIG. 3 is a left side elevational view thereof, the right side being a mirror image of the left side shown; and

FIG. 4 is a rear elevational view thereof.

We claim:

The ornamental design for a calculating machine, as shown and described.
